NON-REFILLABLE BOTTLE.

Specification of Letters Patent. Patented May 23, 1916.

1,184,139.

Application filed January 13, 1915. Serial No. 1,899.

To all whom it may concern:

Be it known that I, SIGMUND SCHIFF, a subject of the Emperor of Austria-Hungary, residing in the city, county, and State of 5 New York, have invented certain new and useful Improvements in Non-Refillable Bottles, of which the following is a specification.

This invention relates to a bottle-refill preventer and has for a main object to provide such a refill preventer which will automatically lock when it is attempted to refill the same even when the pressure inside the bottle has been reduced.

Still another object of the invention is to 15 provide a refill device which will not require any jolting whatever to open the same for pouring.

Among the particular objects of this invention it is aimed to provide a valve for a 20 refill preventer which is light enough to be affected by the rise of liquid such as whisky and the like beverages, and yet not flow on top of such liquid, and on the other hand be sensitive to the movement of a weight; a 25 weight for actuating a valve which is tiltably supported with its weighted end resting against the valve; a refill preventer device in which the capillary action of the flow of liquid will coöperate with the ribs formed 30 in the inside of a bottle neck and combine with a tilttable weight to actuate a valve into closed position. These and other features, 35 capabilities and advantages of the invention will become apparent from the subjoined detailed description of one specific embodiment thereof illustrated in the accompanying drawings in which—

Figure 1 is an axial section of a bottle neck when the bottle is in erect position, 40 showing the refill preventer in closed position. Fig. 2 is a view similar to Fig. 1 showing the refill preventer in open position when the bottle is tilted with its neck pointing downward. Fig. 3 is a similar view to 45 Fig. 1 showing the bottle in horizontal position and illustrating the respective positions of the elements of the refill preventer when the bottle is in such horizontal position. Fig. 4 is a similar view to Fig. 1 in 50 which the bottle is turned upside down, the pressure has been reduced and the inrushing liquid has locked the valve. Fig. 5 is a transverse section along the line 5—5 of Fig. 1. Fig. 6 is a plan view showing one form 55 of locking means for locking the refill pre-

venter in the bottle neck. Fig. 7 is an axial section of a bottle neck similar to Fig. 1 with the refill preventer removed. Fig. 8 is a fragmental view of the mouth of a bottle showing another form of locking means for 60 locking the refill preventer in the bottle neck.

In the embodiment shown, a bottle neck 1 is provided with an annular recess 2 at the lower end of such bottle neck having its 65 outer end 3 of less diameter than the bottom of the recess which is adjacent the inner end of the recess. The inside of the bottle neck is provided with circular ribs 4 and disposed between and extending from one circular rib 70 to another circular rib are axially extending ribs 5 (Fig. 7). When the locking means illustrated in Figs. 1, 3, 4 and 6 are used, there is provided an annular recess 6 near the outer or upper end of a bottle neck. At 75 the outer end of the bottle neck or mouth of the bottle, there is provided an outwardly tapering rabbet 7.

In the recess 2, there is provided a valve seat 8 preferably composed of a collar 9 having an annular rabbet 10 in which is positioned a washer 37 of a composition such as cork, this washer 37 being of greater diameter in the present instance than the diameter of the collar 9 so that when the seat 80 is forced into position in the rabbet 2, the cork washer 37 will be at the inner end of the valve seat and due to the narrow outer portion 3 of the recess 2, will lock such collar 9 in position. The outer surface of the 85 collar 9 is preferably polished to form an adhesion surface and serves to engage the polished surface 11 of the valve 12 which is 90 preferably composed of two buttons 13, 13, each having a short stem 14 centrally disposed thereof to engage in a central opening 15 formed in a cork member 16, one button being positioned at each end of such cork member 16, and the cork member being of 95 cylindrical conformation and of less diameter than the outside diameter of the buttons. 100

The button 13 which is disposed nearer the mouth of the bottle is preferably of less diameter than the button 13 which is disposed in the inner end of the bottle neck so 105 that when the bottle is disposed in a horizontal position, the valve 12 will be disposed in an inclined position as shown in Fig. 3. The outer surface of the outer button 13 is 110 preferably plane against which the convex

surface 17 of the weighted member 18 coacts, such weighted member 18 comprising a cylindrical portion 19 terminating at one end in the convex surface 17 and having formed on its other end an outwardly extending annular portion 20 of greater diameter than such cylindrical portion 19 and having on its outward extending face in a circular line a series of teeth 21 disposed adjacent to the outer periphery of such annular member 20. This weighted member 18 is preferably so formed that the end adjacent to the convex surface 17 is weighted so that, when in a horizontal position of the bottle, the weighted member 18 will be supported on the annular member 20 and tilt in an inward direction due to such adjacent end.

Forming the mouth of the bottle and at the same time the lock for locking the refill preventer in the bottle neck, there is provided a cylindrical member 22 having an annular recess 23 adjacent to its inner end and an annular rim 24 adjacent to its outer end, while the outer end of such cylindrical member surrounding the opening therethrough is extended to form a lip 25. In the annular recess 23, there is provided a spring 26 (see Fig. 6) which spring when the cylindrical member is moved into position will snap into the annular recess 6 formed in the bottle neck. In the rabbet 7 formed on the outer end of the bottle neck and abutting against the annular member 22 of the cylindrical member 30, there is provided another cork washer 27.

In the modified form of locking means shown in Fig. 8, the outer end of the bottle neck is provided with the usual form of annular recess 28 on the outer wall of the neck, and a conical recess 29 on the outer end of the inside of the bottle neck, the outer wall of the bottle neck beginning at the recess 28 and being rounded to form an annular bead 34 at the mouth end of the bottle neck. In this form of locking means, a cylindrical member 30 is inserted having an annular rim 31 at one end thereof, from which end there extends an annular lip 32 formed around the opening through such cylindrical member 30. The annular rim 31 is of greater diameter than the opening with the neck of the bottle. When the cylindrical member is inserted in place, the lip 32 is positioned at the outer end of the bottle neck, and in the conical recess 29 and abutting against the annular rim 31 is positioned a washer 33 preferably composed of cork. Then there is spun around the annular bead 34 a metal collar 35 having one of its annular edges lapping over the annular rim 31 and the other of its annular edges bent into and located in the annular recess 28.

The collar 9 of the valve seat 8, the buttons 13 of the valve 12, the weighted mem-

ber 18 and the cylindrical members 22 and 30 of Figs. 1 and 8 respectively are preferably composed of glass.

The inner end of the weighted member 18 is provided with the convex surface 17 so as to present the smallest adhesion surface possible to the outer end of the button 13 adjacent thereto, it being obvious that with a rounded convex surface only one point would contact with a plane surface at any one time, and thus the frictional resistance between the two members would be so slight as to facilitate a comparatively free sliding movement between the two members which is desirable for the operation aforementioned and also that the action of the weight should be almost central.

The operation of the two modifications is substantially identical and therefore it will suffice merely to describe that of the modification illustrated in Fig. 1 which is as follows: When the bottle is in upright or erect position, the weighted member 18 will rest on the valve 12 and the valve 12 on the valve seat 8, in which position the opening through the collar 9 and therefore to the bottle is closed, as shown in Fig. 1. When it is sought to pour out liquid from the bottle, and the bottle is tilted as shown in Fig. 2, the weighted member 18 and valve 12 still in contact with one another will together travel away from the valve seat 8 until the weighted member strikes and rests against the cylindrical member 22. In this position of the weighted member 18 and valve 12, the liquid as shown by the arrows 35 will travel under the valve 12 and weighted member 18, in which travel it will pass through the grooves formed by the axially extending ribs 5 and the space 105 formed between the buttons 13 on the outer wall of the cork member 16 and through the space formed on the weighted member 18 between the adjacent button 13 and the annular portion 20 of the weighted member 18, then through the spaces formed between the teeth 21 of the weighted member 18, and through the opening in the cylindrical member 30, while the air, to displace the liquid being poured from such bottle, will travel through similar passages in a reverse direction above the weighted member 18 and valve 12, as shown by the arrows 36. At any position of the bottle when the bottle neck were inclined above a horizontal plane, 120 the coöperation of the weighted member 18 and the valve 12, and even the valve 12 alone would act to close the bottle.

When the bottle is shifted from erect position to the horizontal position shown in Fig. 3, in the attempt to refill the bottle, when the air has been evacuated from the inside of the bottle or not, the valve 12, due to the smaller diameter of the outer button 13 than the inner button 13, would permit 130

the tilting of the valve 12 downward in an outward direction. The advantage derived by this arrangement is that the relative lower end of the inner button 13 would always be first in contact with the valve seat 8, and thus even if there were irregularities in the fit between the valve 12 and valve seat 8, this would not affect the operation of the valve at its initial position in which position obviously the greatest likelihood of improper closure would occur. When the lower portion of the valve 12 is so contacting with the lower portion of the valve seat 8, the space left open above would be considerably slight for a short distance and at any rate too small for a drop of liquid to ooze through when the pressure inside of the bottle is equal to that outside. When the liquid that is being attempted to be filled into the bottle is poured into the neck, it would first rise to a considerable level in such bottle neck before it would rise to the level where the space between the valve 12 and valve seat 8 were large enough to permit ingress of such liquid, but as soon as the level of liquid starts to rise a certain distance, and this in practice has been found, due to capillary action and adhesion, to be a distance substantially one-half of the diameter of the bottle neck, the valve would thereby be raised, and the weighted member 18 acting on its outer end would then co-operate with the raising force of the liquid to tilt the valve 12 inward snugly against the valve seat 8. It will be seen that the inner button 13 being of substantially the same diameter as the smaller diameter of the bottle neck could not rise and therefore only the outer button could rise which is desirable to tilt the valve 12 into closing position.

In all positions which are similar to that shown in Fig. 2, the air inside the bottle would prevent the liquid to enter even if the valve were open. If I incline the bottle opposite to the position shown in Fig. 2, that is, below the horizontal with the neck pointing upwardly, whether the air be evacuated from the inside of the bottle or not, the weight of the weighted member 18 and the weight of the valve 12 would co-operate with the capillary action of the liquid to move the valve to its seat.

When the bottle is in erect position as shown in Figure 1, whether the air were evacuated from the inside of the bottle or not, the weight of the refill preventer elements will operate to lock the valve. However, when the air is evacuated from the inside of the bottle, and the bottle is disposed in the position illustrated in Figs. 2 and 4, then the inrushing liquid will lift the valve to its seat and the capillary action will reduce the pressure of the inrushing liquid so that the pressure on the outer end of the valve will be greater than the pressure

on its inner end and by this pressure the valve will be firmly seated.

The axially extending ribs 5 provided in the present invention serve as guides for the valve 12 and weighted member 18, and permit the supporting points to be considerably spaced from one another so as to decrease the tilting tendency of the valve to produce a commercially floating valve. These ribs 5 take the place of the ribs 12 formed on the valve in my prior application, Serial No. 749,086, filed February 18, 1913.

It is obvious that various changes and modifications may be made in the details of construction without departing from the general spirit of the invention.

I claim:

1. In combination with a bottle having a bottle neck, there being axially extending ribs formed in said bottle neck, a bottle-refill preventing device comprising a valve seat, and a valve tiltably mounted in said bottle neck so that its relative lower end will initially engage the relative lower end of the valve seat when said bottle is in a substantially horizontal position, the inner end of said valve being substantially of the diameter of an imaginary circle that may be described to engage the inner peripheries of the axial ribs and supported by said ribs of said bottle, the outer end of said valve being of smaller diameter than the inner end so that the valve will tilt into open position when the bottle is moved sufficiently out of a vertical position, said ribs permitting the passage of liquid between them when said valve is unseated, the valve being sufficiently light so that, upon the entrance of liquid, the outer end will be raised to closing position, the inner end being prevented from being raised by the ribs.

2. In combination with a bottle neck, a bottle-refill preventing device comprising a valve seat, a valve tiltably disposed in said bottle neck, so that its relative lower end will initially engage the relative lower end of the valve seat, said valve being slightly lighter than the liquid for which it is to be used, but sufficiently sensitive to the rise of liquid, and a weighted member to co-operate with the raising force of the liquid to tilt said valve into closing position, the valve moving into closing position when tilted upward by the influx of liquid, the inner end of said valve being anchored against rising with the liquid, but the outer end of said valve being free to rise so that the valve will tilt about said inner end when raised into a closing position.

3. In combination with a bottle neck, a bottle-refill preventing device comprising a valve seat, a valve tiltably mounted in said bottle neck so that its relative lower end will initially engage the relative lower end of said bottle seat, said valve comprising a

- floating portion, and a button secured to each end of said floating portion, said buttons having annularly extending portions on which the valve rests when the bottle is in horizontal position, the annular portion of the inner button being of greater diameter than the annular portion of the outer button and anchored against being raised with the influx of liquid, but the outer button being free to rise so that the valve will tilt about said larger annular portion and be actuated into closing position.
4. In a non-refillable bottle, a device com-

prising a valve seat, a floating valve comprising an inner end and an outer end, the inner end being adapted to seat on said valve seat to close the bottle, and means for anchoring said inner end from being raised by the influx of liquid, the outer end being free to rise so that the valve will tilt about the inner end with the influx of liquid to close the bottle.

SIGMUND SCHIFF.
